ODILON BRISBOIS, OF CHICAGO, ILLINOIS, ASSIGNOR OF FIFTY-ONE ONE-HUNDREDTHS
TO JOHN H. WARE, OF CHICAGO, ILLINOIS.

DEVICE FOR STARTING INTERNAL-COMBUSTION ENGINES.

1,140,831.

Specification of Letters Patent.

Patented May 18, 1915.

Application filed August 4, 1911. Serial No. 642,265.

To all whom it may concern:

Be it known that I, ODILON BRISBOIS, a citizen of the United States, residing at Chicago, in the county of Cook and State of Illinois, have invented certain new and useful Improvements in Devices for Starting Internal-Combustion Engines, of which the following is a specification.

This invention relates to devices for starting internal combustion engines and has for its object to provide a new and improved device of this description.

The invention is illustrated in the accompanying drawings wherein—

Figure 1 is a plan view with parts removed showing the device applied to an automobile; Fig. 2 is an enlarged view showing the valves which control the connection to the engine cylinders; Fig. 3 is a sectional view taken on line 3—3 of Fig. 2; Fig. 4 is an enlarged sectional view taken on line 4—4 of Fig. 2; Fig. 5 is a sectional view taken on line 5—5 of Fig. 1 through one cylinder of the pump; Fig. 6 is a sectional view through the tank used in connection with the device. Fig. 7 is a sectional view through a portion of one of the cylinders.

Like numerals refer to like parts throughout the several figures.

The present device has among other objects to provide a means for starting an internal combustion engine without cranking it.

As illustrated in the drawings I have shown the device applied to a four cylinder gasolene automobile engine.

In the construction herein shown, I provide a receptacle 1 containing a suitable sponging or absorbing material. As illustrated in Fig. 6, this receptacle contains coke or cotton. In the particular construction of Fig. 6, I provide two sections, 2 and 3, of coke and the sections 4 and 5 of cotton. The receptacle 1 is connected to a pump 6 by means of a suitable pipe 7. This pipe is provided with a check valve 7a. This pipe preferably projects into the receptacle so that the end will be embedded in the coke and will be located at a distance from the discharge opening of the tank. Any suitable pump may be used. As illustrated in Fig. 5 each cylinder of the pump is provided with a connection 8, leading to the pipe 7 and a connection 9 leading to the pipe 10, which leads to the source of gaso-

lene supply. The pipe 8 is controlled by a valve 11 which is opened when the piston 12 of the pump moves up and the pipe 9 is controlled by a valve 13, which is open when the piston 12 moves down, the valve 13 being normally sealed by the spring 14. The pipe 10 is provided with a suitable generator valve or carbureter 15, which can be arranged so that a suitable mixture of gas and air can be drawn into the pump and then forced into the receptacle 1. This pipe is also preferably provided with a valve 16 by means of which communication with the carbureter and the gasolene tank may be cut off and a valve 17, by means of which a communication may be made with the atmosphere.

The receptacle 1 is provided with an outlet 18 which is preferably protected by a screen 19. A pipe 20 leads from this outlet to the valve casings 21, 22, 23 and 24 in which are located the valves which control the admission of this gas to the cylinders of the engine. The pipe 20 is provided with a valve 25 which is normally closed. The valve casings 21, 22, 23 and 24 are provided with the valves 26, 27, 28 and 29 which are normally closed so as to close the connection through the pipes 30 to the cylinders 31, 32, 33 and 34 of the engine. These valves are provided with controlling arms 35 which are connected to the controlling part 36. This controlling part 36 in the present instance is provided with an end piece 37 in reach of the foot of the operator so that the operator can open the valves by pressing thereon. The valve 25 is also provided with a controlling lever 38. This controlling lever is arranged so that it will not be operated to open on the valve 25 during the first portion of the movement of the part 36, but is only actuated to open said valve at the end of the movement of said part 36. This result is secured by having the lever 38 connected with the part 36 by means of the slot 39, see Fig. 3. The valve casings 21, 22, 23 and 24 are each provided with a valve 40. Each valve 40 has an annular groove 41 which connects with the passageway 42, communicating with the pipe 20. The end 43 of the valve 40 is slightly less in diameter than the part end which it has received so that a certain amount of the gas can blow past it when the valve is closed as shown in Fig. 4. This end is also preferably

slightly beveled. Each valve 40 is normally held in its closed position by means of a spring 44 and is prevented from engaging the seat 45 by a suitable stop 46.

5 The valve casings 21, 22, 23 and 24 are fastened in place in any desired manner. As herein shown they are held to a supporting piece 47 which is connected to the frame of the machine. A suitable gage 48 is located so as to be easily seen by the operator and is connected in the system so that the pressure of the gas therein may be easily ascertained. The pump 6 is adapted to be connected with the engine shaft 49 so as to 10 be actuated therefrom, any suitable means being provided for disconnecting it from the engine shaft when the desired pressure in the receptacle 1 is secured. The pump 6 may be used to pump air into the tires if 15 desired. For this purpose the pipe 7 is provided with a valve 50 so that the communication with the receptacle 1 may be closed and with a branch pipe, 51, having a valve 52 by which it is controlled, said branch pipe adapted to receive the flexible tube 53 20 which can be connected with the tire.

I have described in detail a particular construction embodying the invention, but it is of course, evident that the parts may 30 be varied and some of the parts used with others not herein shown without departing from the spirit of my invention.

It will further be noted that there is here 35 provided a selecting device which automatically selects the proper cylinder and connects it with the source of gas supply so that a charge of gas will be inserted in such cylinder, the piston of the cylinder being then in such position that the ignition of the 40 gas will start the engine.

Any suitable sparking arrangement may be used. For purpose of illustration I have shown in Fig. 7 a section of one of the cylinders showing the piston 32^a and the spark plug 54 with the sparking points 55 and 56. The conductors 57 and 58 are connected in 45 the sparking circuit in the usual manner.

The use and operation of my invention are as follows: When the engine is in 50 operation the pump 6 is connected therewith so as to be operated and the proper amount of gas is pumped into the receptacle 1. The pressure in this receptacle may be anywhere say, from ten pounds to one hundred pounds. 55 The pump is then stopped. Under these conditions the valves 16 and 50 are open and the valves 17 and 52 closed. If now, the engine is stopped and it is desired to again start it, the operator without getting out of the car, pushes upon the end piece 37 so as to move the part 36. This movement opens the valves 26, 27, 28, and 60 29 and after these valves have been opened the final movement opens the valve 25 so 65 as to let the gas pass from the receptacle 1.

If for example, a four cylinder, four cycle engine, as shown in the drawings is used, the pistons of the engine, when the engine is stopped, will be approximately at the middle of their stroke and one cylinder will 70 be open to the exhaust and another open to the admission pipe, the other two cylinders will be closed, one having just past the firing point and the position of the other moving up to the compression point. If now, the valves 26, 27, 28, 29 and the valve 25 are 75 opened, the gas from the receptacle 1 escapes past the ends 43 of the valves 40 and enters the cylinders of the engine. The pressure in the two cylinders that are closed will rise 80 more rapidly than the pressure in the other two cylinders and when this pressure reaches a predetermined amount, the valves 40 associated with said cylinders will be 85 automatically opened so that the gas from the receptacle 1 is free to flow rapidly into the cylinder. Before the pressure in the cylinders can become too great, the valves 40 connected with the other cylinders also 90 open and thus relieve the pressure, the gas taking the path of least resistance and flowing into the cylinders which are open and out through the openings so as to relieve the 95 pressure. The part 36 is then released and is preferably automatically moved by means 100 of a suitable spring so as to close the valves 25, 26, 27, 28 and 29. The sparking device for the cylinders is adjusted so that the cylinder which has just had an explosion will 105 receive a spark and the gas will thus become ignited and the piston moved so as to start the engine. The gas in the other cylinders will then also act in proper succession so as to insure the proper movement of the engine until gas from the carburetor is drawn in 110 so as to keep the engine in motion. It will be seen that by means of this arrangement the valves 26, 27, 28 and 29 are opened before connection is made with the receptacle 1 and that the device automatically acts to 115 force the gas into the proper cylinder and to relieve the pressure so that injury to the engine is prevented. It will further be seen that the engine can be easily and quickly started while the operator is in the car by 120 simply moving the part 36 and properly adjusting the spark. It will further be seen that since the engine can be started with a comparatively low pressure in the tank, say 125 pressure of ten pounds or even lower, it is a comparatively easy matter to keep sufficient pressure in the tank, particularly in view of the fact that it is not the pressure in the tank that moves the engine, said pressure being simply used to force the gas into the 130 cylinders.

The device may be applied to any automobile and supplied with any of the ordinary sparking devices.

While I have shown the device used with 130

a four cylinder engine it can be used with any other form of engine.

The action of the absorbing material in the receptacle 1 is of great importance in the commercial and practical operation of the starting device. By using absorbing material like coke and cotton, I find that the gas is absorbed thereby and kept in proper condition for long periods. This arrangement prevents the gasoline from condensing at the bottom of the tank. When this arrangement is used a receptacle is ready to supply the proper explosive mixture at any time. It will thus be seen that by means of this device I provide an automatic starting device which is reliable, which can be easily operated from the car and which can be applied to any ordinary automobile, it being simply necessary to connect the receptacle, pump, valves and connections to the frame of the machine.

If it is desired to use the pump to pump up the tires, the flexible tube 53 is placed on the branch pipe 51 and is connected with the tire. The valves 16 and 50 are then closed and the valves 52 and 17 opened. The pump is set in operation and then pumps the cool air drawn from the outside atmosphere directly into the tire.

I claim:—

1. A device for starting internal combustion engines comprising a source of supply of combustible gas, a connection between said source of supply and each of the several cylinders of the engine, manually controlled valves by means of which said connections are controlled and additional valves in said connections, said connections constructed to permit a flow of said gas therethrough when said manually controlled valves are open and said additional valves are closed, and said additional valves so constructed that through the agency thereof the proper charge of gas is automatically inserted in the proper cylinder of the engine when the manually operated valves are opened.

2. A starting device for internal combustion engines comprising a source of supply of explosive gas, a connection leading from said source of supply to each of the cylinders of the engine and an automatic valve in each of said connections adapted to be opened by the pressure in the engine cylinders so as to permit the flow of gas into the engine cylinders when the pressure therein reaches a predetermined amount.

3. A starting device for internal combustion engines comprising a receptacle for receiving explosive gas, a pump for pumping such gas into said receptacle, a quantity of coke in said receptacle, a connection between said receptacle and each of the engine cylinders, an automatic valve in each of said connections adapted when the pres-

sure in any cylinder reaches a predetermined amount to automatically open and permit the flow of the gas into said cylinder.

4. A device for starting internal combustion engines comprising a source of supply of explosive gas, a connection from said source of supply to each of the cylinders of the engine, two sets of valves in said connections, means on the car for simultaneously opening one set of the valves, the valves of the other set being automatic so as to be automatically opened when the pressure in the cylinder associated therewith reaches a predetermined point during the period the first set of valves are opened.

5. A starting device for internal combustion engines comprising a source of supply of explosive gas, a connection leading from said source of supply to each of the cylinders of the engine, a manually operated valve in each of said connections, an automatic valve associated with each of said connections arranged normally to permit a small quantity of gas to flow through the said connections, and means for automatically opening said valves responsive to the pressure in said cylinders.

6. A device for starting internal combustion engines comprising a source of gas supply, means to supply gas to said cylinders to flow through the open ones thereof and into the closed ones, means for automatically connecting the closed cylinders with said source of gas supply to obtain a larger flow of said gas thereto and to increase the pressure of said gas therein.

7. A device for starting internal combustion engines comprising a source of gas supply, a connection from said source to each of the cylinders of the engine, an obstructing device in each of said connections for diminishing the flow of gas to the cylinders and means for automatically moving, by means of the pressure of gas in the said cylinder, the obstructing device in any of said connections when the piston in the cylinder to which the connection leads is in a position to be moved to start the engine when the charge of gas is ignited.

8. A device for starting internal combustion engines comprising a source of gas supply, a connection leading from said source of gas supply to each of the cylinders of the engine, said connection adapted to permit a continuous flow of gas therethrough to all said cylinders, and a selecting device adapted to be automatically operated by a determined pressure of gas on the discharge side thereof, for selecting the proper cylinder into which a charge of gas from said gas supply is to be inserted when it is desired to start the engine, and thereby permit a large flow of said gas to said selected cylinder.

9. A device for starting internal combustion engines provided with a plurality of cylinders comprising a source of gas supply, a connection leading from said source of gas supply to each of said cylinders, an obstructing device in each of said connections adapted to permit a determined continuous flow of gas through said connections, and means actuated by a determined pressure of gas in said cylinders, to move the obstructing device in the connection leading to the cylinder into which the starting charge is to be first ignited so as to permit unobstructed flow of the gas into said cylinder while the obstructing devices in the connections leading to the other cylinders remains in its obstructing position.

10. A device for starting internal combustion engines comprising a source of gas supply, means to provide a continuous determined flow of gas from said gas supply to all the cylinders of said engine, means for automatically connecting, by pressure attained therein, certain of said cylinders with the source of gas supply to increase said determined flow of gas thereto, while the flow of gas to other of such cylinders continues as first determined.

11. A device for starting internal combustion engines comprising a source of gas supply, means for connecting said cylinders to said source of gas supply, means to automatically enlarge said connecting means with the closed ones of said cylinders while the supply of said gas to the open ones thereof continues unchanged, and means to automatically successively enlarge said connecting means subsequent to the closing of said open cylinders and previous to the ignition of the charges in said closed cylinders.

12. A device for starting internal combustion engines comprising a source of gas supply, a connection adapted to continuously

discharge gas therethrough leading from said source of gas supply to each of the 45 cylinders of the engine and an automatically actuated selecting device operated by a determined pressure of gas on the discharge side thereof, for selecting the proper cylinder into which a charge of 50 gas from said gas supply is to be inserted when it is desired to start the engine, said selecting device operating to change the flow of said continuous discharge of gas to said selected cylinder, and means for igniting 55 said charge of gas so as to move the piston in said cylinder.

13. A device for starting an internal combustion engine which is provided with a plurality of cylinders, comprising a receptacle 60 adapted to contain a fuel mixture under pressure, and passage ways communicating with said cylinders and with said receptacle, in combination with means to establish restricted continuous communication between 65 said passage ways and said cylinders, said means actuated automatically by pressure on the discharge side thereof to establish unrestricted communication between a passage way and its corresponding cylinder 70 when a determined pressure is attained in said cylinder.

14. A device for starting internal combustion engines comprising a source of explosive gas, connections leading therefrom to 75 the cylinders of the engine, two valves in each connection, one a manually operated valve, the other valve operated by pressure in its corresponding cylinder.

Signed at Chicago, Illinois, this 29th day 80 of July 1911.

ODILON BRISBOIS.
